UNITED STATES PATENT OFFICE

PHILIP N. BRAUN, OF SYRACUSE, NEW YORK, ASSIGNOR, BY MESNE ASSIGNMENTS, TO THE PROSPERITY COMPANY, INC., OF SYRACUSE, NEW YORK, A CORPORATION OF NEW YORK

AUTOMATIC TRAY PRESS

Application filed May 16, 1924, Serial No. 713,699. Renewed December 12, 1929.

This invention relates to combination conveyor pressing machinery and more particularly to automatic tray presses; and one of the main purposes is to improve the tray pressing machine disclosed in my joint application for Patent Serial Number 708,756 filed April 19, 1924, to the end that the entire machine be power driven and automatic in operation.

A further object is to produce improvements in respect to pressing machinery and garment handling means whereby the work is more rapidly placed within the press and removed therefrom; and to this end my invention is so constituted that the press operator stands from the vicinity of the press jaws rendering personal accidents impossible. The garment is spread out upon a flat conveyor or tray surface where visibility of the work on the tray is exceptionally good and the operator is not hampered by having to spread the garment across and into the hot press jaws; and since he does not work inside the press jaws, the press head is not required to open so high above the buck which affords simple construction and requires less power to open and close the press than in wide opening long stroke pressing jaws.

Furthermore, my improvements increase the working efficiency of pressing machines as regards the production, in that the quantity of work turned out is somewhat increased because the operator does not lose time between pressing periods for while one garment or set of garments is being treated in the press or heating zone, the operator is engaged in removing the pressed garments from the trays and spreading out unpressed garments on the conveyor and making ready for the next pressing operation and period. For the purpose of illustrating the invention, the accompanying drawings show a two-part or multi-unit garment or work conveyor, but other forms, or even a single conveyor, may be incorporated into the pressing machine; and a feature of the invention is the roll in and roll out double tray or work carrier which crosses one over the other in approaching and leaving the press. The conveyor improvements constitute a large saving in floor space for the reason that, regard-

less of the size of the conveyor tray, apron or other means for holding the garment, the space set aside on the machine for the conveyor is substantially equal to the area of one conveyor tray only while in fact the conveyor is double capacity in that two trays are provided. While garment forms, trays, conveyors and the like, have been suggested for use in connection with pressing machines they have occupied too much space because the floor area covered by the machine usually equals twice that of the spread or area of the pressing jaw members which was due to the fact that as one tray or conveyor unit moved into the press from one side, the other tray bearing the finished goods was ejected from the press on the other side; and therefore the actual floor space required for an ordinary conveyor press was usually about three times the area of one of the press jaws.

I employ a back and forth conveyor, the units of which pass each other going in opposite directions, and which are moved in and out of the press from one side of the machine only. While my conveyor cars or trays are illustrated as traveling on tracks, my invention is not limited to such construction.

The drawings

Figure 1 illustrates a side view of my improved combination power driven garment press and automatic tray conveyors, the pressing jaws being closed down upon the work with one tray in the press and the other tray outside thereof in unloading and reloading position; and Figure 2 illustrates a plan view thereof with the garment press head removed to expose the one tray in pressing position above the buck.

Figures 3 to 6 inclusive illustrate a series of side views of the tray conveyors in their several different positions for the purpose of more clearly disclosing the traveling movement of said trays; and furthermore these views portray the mode of operation characteristic of the tray conveyor hauling means which consists of an automatic catch and release device whereby the carriage runs forwardly free of all trays carrying no trays at all in its forward stroke away from the

press jaws, but the carriage picks up a tray at the outer end of its travel and then stands ready to haul in the tray bearing the new work when the press jaws start to close. In this respect my improvements are so laid out that during the opening stroke of the press jaws the conveyor remains at rest but when the jaws start to close the trays likewise start movement and then we have an automatic simultaneous jaw closing and conveyor traveling function which is a feature of my invention. However, it is to be appreciated that the opening cycle of the jaws may as well be synchronized with the tray movement, but in the present description I have chosen the press closing cycle as the one by which the tray movement is associated.

Figure 3 shows the two trays in their limited position of travel, namely, one tray being in pressing position and the other being outside of the press to deliver old work and receive new work. Figure 4 shows the trays crossing one over the other. Figure 5 illustrates the completion of the overhead crossing movement whereby the right hand tray of Figure 3 has completed its outward travel and has exchanged positions as compared to the position of the trays in Figure 3. Figure 6 shows the trays in the same position as in Figure 5, but a traveling carriage member is in the act of starting forwardly to pick up the outer tray for the purpose of moving it inwardly with its work to the pressing jaws.

Figure 7 shows a plan view of one set of rails in the track system which permits the roll in and out movement of the trays whereby one is caused to cross over the other.

Figures 8 and 9 illustrate cross sectional views taken on the lines 8-8 and 9-9 respectively of Figure 7.

Figure 10 shows a diagram of the trays connected by a flexible cable whereby the movement of one conveyor tray is transmitted to the other tray; and Figure 11 shows a similar diagram with the exception that the trays are in reversed or exchanged position.

A description will first be given of a suitable form of pressing machine for the purpose of more comprehensively explaining my improvements in respect to power operated tray conveyors; and thereafter the conveyor system will be described and set into the press.

The pressing machine

A pressing machine frame in Figure 1 consists of legs 15 which support a bed or press buck 16 over which is disposed a pressing head 17 which raises and lowers in relation to the buck or bed 16 for pressing the work disposed therebetween and it is understood that said work is conveyed to and from the press bed, into the press jaws, by the tray

conveyors hereinafter described in detail. The numeral 12 designates the meeting jaw or pressing surfaces and is the pressing plane. A press lever 18 is pivotally mounted on a shaft 19 carried in the frame 15 and the outer lower end of the lever 18 projects downwardly where it pivotally connects with a connecting rod 20 which is reciprocated by a crank or driving wheel 21 anchored to a power driven shaft 22 carried in a gear housing 23. The connecting rod 20 has its outer end pivoted at 24 on the lower end of the press lever or yoke 18 while the front end thereof is mounted on a pin 25 forming part of the power driven crank or driving wheel 21. A motor 26 has a main drive shaft 27 journaled in the gear housing 23 and acts to rotate the power shaft 22 for the purpose of reciprocating the connecting rod 20 in order to rock the press lever 18 back and forth on the shaft 19 for the purpose of raising and lowering the head. It is to be understood that any suitable motive power means may be employed for reciprocating the connecting rod 20 and in this connection the crank or drive wheel 21 may be directly connected to the press lever 18 or assume other relations with the press lever so long as a rocking motion is imparted to the press lever.

A continuously running or stop and start motor may be employed for causing the head to dwell on the buck to prolong the pressing operation. In the present case the former type motor means is employed and so clutching mechanism may be used for stopping and starting the driving wheel or crank 21. It is understood how any well known type clutch may be employed for driving the connecting rod 20 to outward pressing position as in Figure 1 and then produce a half revolution of the crank driver 21 to pull up the head. A control handle 28 is placed at the front of the machine in convenient reach of the operator to stop and start the motor 26 or the crank driver 21 and is designed to oscillate a shaft 29' through a universal joint if needed. A pendulum bob 14 is anchored to the shaft 29' and swings freely against and cooperates with a clutch lever 13 for appropriately controlling the motor or power shaft 22 whereby the shaft is caused to make a one-half revolution to open the press and another half revolution to close the press. The lower end of the clutch lever extends into the gear housing to control the clutching mechanism but since I do not claim the clutch it is not shown in detail.

The above described pressing machine preferably embodies a relatively short stroke pressing head 17 for it will be understood how pressing jaws are required to open a short distance only inasmuch as the work is not spread upon the buck 16 but is spread upon one of the trays and thereafter travels into the press. Extended visibility of the

buck 16 is not important for the operator has an unobstructed view of the tray upon which he spreads the garment. In this I have made a distinct improvement and advance in the art for with the advent of wide opening modern type garment presses the producer has concerned himself with the development of means for lifting the head high above the buck which sometimes requires complicated structure all of which my invention eliminates.

Since the press head 17 is of substantial weight, it is desirable to counterbalance it in such a way that it readily moves up and down without strain on the motor driving mechanism; and to this end the frame 15 has a rearward projection on which a bell crank arm 10 is fulcrumed at 5. The long arm 10 of the bell crank is provided with a counterbalance weight 9. The upstanding short end 8 of the bell crank carries a pin 7 which floats in a slot 6 made in the lower arm 18 of the press lever. The substantially heavy weight 9 therefore acts through the rather long lever arm 10 against the press lever 18 to exercise a lifting force against the head 17 whereby the said head and the said counterbalance weight are made to approximately balance one with the other to permit a smoothly operating mechanism and to avoid over-working the motor 26 during the head lifting motion.

The conveyor

In the first place the conveyor occupies little space because of its overhead crossing function and is automatic in operation. A rectangular tray frame 30 is usually constructed a little larger than the pressing jaws of the machine with which the trays are to be used, and a canvas stretcher 31 is held tautly in the frame 30 by lacings 32; and the stretched canvas work carrier 31 conveys the garments to the press jaws. For convenience in description, one of the trays is denoted by 30 while the other tray is pointed out by the numeral 29. The tray 30 may at times also be referred to as the upper tray and the tray 29 as the lower one, though no such distinction in fact exists for a novel feature is the means whereby both trays come to rest in the same plane when inside the jaws. However, the tray 30 travels above the tray 29 in its back and forth travel. In Figure 2 the press buck 16 is shown disposed underneath the lower tray 29 which illustrates how one garment tray is left in pressing position for treatment of the work or garment thereon while the other tray 30 is held in outward position in front of the press for the purpose of enabling the operator to remove the finished garment and place new unpressed garments thereon.

The trays 29 and 30 are constructed in duplicate which decreases the cost of production; and a corner anchor bracket 34 is fas-

tened at each of the four corners of both of the trays and are provided with shafts 35 upon which are mounted track rollers. Rollers 36 are carried by the tray 29 and run along the inner track rail 37. The said tray 29 undergoes a straight back and forth movement in and out of the press jaws along the track 37 and comes to rest inside the press with its canvas stretcher coincident with the pressing plane 12. The tray 30 is fitted with front rollers 38 which are adapted to roll on the track rails 39 while the rear edge of the tray 30 is equipped with outside wheels or rollers 40 adapted to travel upon the outer track section 41.

My improvements constitute means for crossing one conveyor tray over the other as already suggested during the in and out or back and forth travel to and from the press, and one means to this end resides in the novel track structure illustrated, but other facilities may be employed to accomplish this result without departing from the principle of the invention. It is to be noted that the inner track rails 37 are made full length 90 extending from the rear edge of the press jaws to the front end of the conveyor frame 11 support which holds the track in proper position. This permits the tray 29 to run the full length of the simple track 37 and pass 95 underneath the tray 30. On the other hand, the outer track 39-41 is made in two sections, as denoted by the numerals 39 and 41, and the rear tray wheel shaft 35 reaches across the track rails 37 and 39 in order to find support 100 on the outer upper track section 41. The forward end of the track 37 may be bent down at an angle to the horizontal as well as the front track sections 39 for the purpose of bringing the tray to outward rest where it 105 is held in convenient angular position for the loading thereof. The inner track system alongside the pressing jaws is horizontally disposed and so constructed as to cause the conveyor stretcher supports 31 to move into the pressing plane 12, and this is characteristic of both track systems. The upper and lower guide track means or track system 37, 39 and 41 affords guide means on which the two work carriers 29 and 30 pass each 110 other in back and forth movements to and from the press jaws.

It is to be noted that one of the trays, in this instance 30, has its rollers or wheels mounted upon two separate tracks. The forward rollers 38 roll upon the short track sections 39 while the rear wheels 40 roll back and forth on the short rear outer track section 41. The object of this structural arrangement, as aforesaid, is to cause one tray to travel past 115 the other in a back and forth movement. By observing Figure 1, it is noted that the wheels 40 of the tray 30 may travel along the track to the rear of the press jaws and come to rest on the rear end of the rails 41 which rolls the 120 125 130

tray 30 into the pressing plane 12, and simultaneously therewith the front wheels 38 of the same tray come to rest on the rear end of the track rail 39, assuming of course the said tray 30 is moved back into the press when the jaws thereof are open. As the tray 39 moves forward out of the press jaws, it rolls along the entire length of the rails 37 and comes to rest on the front end thereof underneath the position originally occupied by the tray 30.

A flexible connection 43 connects the front edges of the trays and passes around a roller 44 while flexible connection 45 is established between the rear edges of the two trays and passes around a roller 46. It is observed that the movement of one tray initiates the movement of the other thereby causing the two trays to move in unison. The operator having loaded the tray 30, is not required to manually roll it back into the press jaws for the power means performs that function as will be seen.

Tray operating mechanism

An improved feature of this invention is the employment of means for automatically running the conveyor trays in and out of the pressing machine back and forth on the guide tracks synchronously with the opening and closing of the press. It is to be noted that the pressing head closes down upon one tray and the work as shown in Figure 1, and during the application of pressure thereto the other tray is at rest in outstanding position for the purpose of having the work removed therefrom and new work spread thereon. In driving the two trays in and out by power, the same motor means 26 is employed and a connection is established between one of the trays and some moving part of the pressing machine which automatically operates the trays as the pressing head closes down to the end that one tray moves in and the other moves out of the pressing machine during the downward cycle of the head 17.

For the purposes of this description it should be understood that the fulcrum shaft 19 is preferably anchored to the press lever 18 and the shaft 19 therefore oscillates during the up and down motion of the head; and this oscillating motion is translated into rectilinear tray motion by means to be described.

A main operating arm 60 has its upper end anchored to the oscillating shaft 19 thereby causing the lower end thereof to swing back and forth during the up and down motion of the head. The lower end of the arm 60 is fitted with a pin 61 which floats in a slot 62 made in a supplementary arm 63 which has its lower end pivotally mounted on the frame as at 64. This construction permits the main arm 60 to swing the upper end of the oscillating arm 63 through a large radius by virtue of the pivot point 64 being located substan-

tially close to the pin 61. The two arms 60 and 63 are therefore so mounted and arranged as to afford a travel at the upper end of the arm 63 about equal to the distance traveled in and out by the trays.

A link 66 has one end thereof pivotally connected to the arm 63 and the front end thereof is pivotally connected by pin 67 to a slide 68 confined in a link guide bar 69. The guide bar 69 is made with a slot 70 in which the slide 68 is confined thereby permitting the said slide to run from rear to front without a tray and reverse its movement carrying a tray. The front end of the guide bar 69 is preferably located just a little lower than the rear end thereof which permits the slide 68 to run down hill in its outwardly forward movement. The two ends of the guide bar 69 are provided with brackets 71 by which the said guide is anchored to reach bars or bracket frames 11 extending from the rear of the machine to the front track extremities thereof to support the several tracks and the guide in rigid relation upon the frame or legs 15 of the pressing machine.

The main purpose of the slide 68 is to travel outwardly in disconnected manner from the conveyor during the rising motion of the head and to pick up a conveyor tray at the end of its outer stroke and stand ready to drive the trays on the track, one in and one out, when the head 17 moves downwardly toward the buck; and to this end the slide 68 is fitted with a pair of automatically operating hooks adapted to engage their respective trays 29 or 30 when the slide block reaches its extreme outward position as will now be described.

In describing the structure and function of the slide 68, reference is made further to the drawings and particularly the series of views as aforesaid; and in the views Figures 3 to 6 inclusive and Figures 10 and 11, the tracks are omitted for clearness in illustration. The slide 68 is confined in the slotted guide 69-70 and adapted to reciprocate back and forth therein under the throw of the link 66 for the purpose of synchronously moving the trays 29 and 30 in and out of the pressing jaws during one cycle of the jaw motion. Since the trays are connected together, as by a flexible cable, it is necessary to pull one tray only which tray thereby causes the other one to travel in the opposite direction. It is to be noted that the opening cycle of the press jaws, the lifting of the head, is utilized for actuating the conveyor trays, because both cycles, the up and down head motion, would not afford satisfactory conveyor operation for the reason that excess conveyor travel would ensue; and so it becomes necessary to establish a connection between the conveyor and press operating mechanism during one cycle of the head operation and to release or disengage said connection during the other

70

90

95

100

105

110

115

120

125

130

cycle of the head movement. In the present disclosure I have chosen the closing press motion as most convenient for illustrating the principle of automatically driving the conveyor from the press operating means.

5 The slide 68 carries a pair of tray hooks and each hook is adapted to individually pick up its respective tray at the end of the outward stroke of the slide and draw the tray back into the press jaws which action of course runs the other tray out of the press. The hook 300 is adapted to pick up the tray 30 and carry it into the press while the hook 290 is adapted to pick up the tray 29 and convey it into the press. Both of the hooks are pivoted on pins 75 anchored in the slide block 68 and each hook is centralized by a spring 76. One end of the spring 76 is fastened to the swingable hook while the other end of the spring is anchored to the slide block. The tension of the springs 76 act to centralize the hooks in normal operating position and each hook is permitted to flex up or down, as the case may be, for the purpose of executing the several functions required of these tray pick up hooks. The upper tray hook 300 is made with an inclined or cam shaped head 77 the purpose of which is to permit the hook to slide past a pin 78 anchored to the tray 30. When the slide 68 travels forwardly sufficiently far along the track, the inclined face 77 slides past and underneath the pin 78 and the said hook 300 snaps into engagement with the pin 78 as shown in Figure 3 which makes a connection between the conveyor 30 and slide 68; and when the slide travels rearwardly towards the jaws the tray 30 is caused to traverse the track and quickly move into the pressing plane 12 thereby causing the trays to exchange positions. As the slide 68 starts traveling to the right from the position in Figure 3 and approaches the position in Figure 4, the spring 76 permits the hook 300 to work upwardly compensating for the up hill travel of the tray 30, for it is to be appreciated that the said upper tray 30 must travel high above the outcoming tray 29 in order that the trays pass one over the other going in opposite directions, and so I have designed 45 the oscillating tray hook 300 having capacity to maintain fixed connection with the tray 30 but at the same time swing on its pivot 75 to compensate for the somewhat irregular travel of the tray 30. As the tray 30 approaches 50 the press jaws it must necessarily run down hill on its track in order that it reach the common pressing plane 12 and here again the spring 76 exercises a centralizing effort on the said tray hook 300 to straighten it out as shown in the position of Figure 5. By the time the tray 30 reaches the pressing position inside the jaws, the head 17 has closed down upon the work and the other tray 29 has 55 reached the outer position shown in Figure 5.

The next operating cycle comprises the lifting of the head.

By reference to Figure 5 it is noted that the slide 68 is in the act of traveling forwardly to the left and such movement is initiated by the thrust of the link 66 operating under the thrust of the links 60 and 63. When the slide 68 starts to the left, the tray hook 300 readily releases from the pin 78 and travels outwardly in centralized position thereby leaving the tray 30 in the press.

70 The lower tray hook 290 is made with an upper cam face 80 which permits it to be depressed by the pin 78 as the carriage slide 68 moves rapidly outwardly since the hook 290 springs down underneath the pin 78 and leaves the conveyor tray 30 at rest in the press jaws. The hook 290 is also made with an underneath cam face 81 which causes the hook to swing upwardly over the pin 82 anchored to the tray 29 and establish a positive connection with the said tray pin 82 as shown in Figure 10. The action of the underneath cam face 81 is shown as taking place in Figure 6 by thrusting upwardly on the hook 290 to establish said connection between the slide 68 and tray 29. Once the hook 290 has snapped into the position over the pin 82 the slide thereafter will haul the tray 29 back into the press and exchange its position for that of the tray 30. Figure 10 shows the hook 290 engaging the tray 29 while at rest in pressing position and by the time this position is reached the press head has closed upon the work and tray 29. As the slide again moves forwardly, the hook 290 moves away from the tray 29 for the hook 290 parts from the tray 29 leaving said tray in position within the press jaws. The offset position of the hook head permits it to move away from the tray pin 82 when the slide 68 moves forward away from the tray 29 to leave it in the press.

80 Preferably the link 66 which forms part of the operating mechanism is capable of slight relative extension and for this purpose incorporates the spring plunger 84 which for all practical purposes possesses a spring sufficiently strong to pull first one tray and then the other tray into the press jaws without compressing to any appreciable extent. Since the trays roll very easily over the track, there exists no compression of the spring 84 until the head 17 closes down upon the work but at this stage of the operation it is appreciated how the tray must stop still in the jaws 90 at the instant of the imposition of final pressure by the motor. In other words the head 17 clamps down on the work on the tray which stops the tray movement, and since the imposition of final heavy pressure on the work 95 may cause slight additional or excess travel of the arm 63 after the tray has ceased to travel, it follows that lost motion or relative motion must occur between the stationary tray and slightly moving press mechanism.

85

90

95

100

105

110

115

120

125

130

In other words the arm 63 may be caused to move the link 66 after the tray has in fact stopped still, and the spring plunger 84 permits this compensation to ensue without damage to the machinery.

Complete and joint operation

Assuming that one tray is in the press undergoing pressure, the operator then has time to unload and reload the outstanding tray. He swings the handle 28 to cause a forward movement of the connecting rod 20 which lifts the head off of the work and rapidly moves the slide 68 forwardly causing it to pick up the outer tray; and the motor drive mechanism continues until the wheel or crank 21 makes a complete revolution which performs the double function of simultaneously exchanging tray positions and closing the head down. The motor or its clutching mechanism is timed to automatically stop after the press head has completed both cycles of operation whereby it rises and falls in relation to the buck in rapid motion and dwells under pressure in position of Figure 1 until the operator again swings the handle 28 to repeat the operation.

No time is lost in pressing on the machine for one observes that I preferably employ motor means adapted to continuously execute the opening and closing press head movement once the operator actuates the control handle 28. In other words both the opening and closing cycle follows rapidly one after the other which is unlike old pressing machines now in use because in the old machines the head must remain up until the work is removed from the buck and new work placed thereon but not so in my machine for I have so designed the head lifting mechanism that it rises a very short distance off the buck and instantly goes back down for by this time the tray with new work has automatically moved into place for pressing treatment.

What I claim is:

1. A machine comprising a press having jaws including a heating zone into which the work is conveyed for heat treatment, drying, pressing and the like, in combination with conveyor means carrying the work and moving it into and out of the zone, separate units constituting said conveyor means, guide means cooperating with the separate conveyor units permitting said separate units to pass one by the other in opposite directions when entering and leaving the zone, and a single power means to open and close the press and for moving the conveyor units in and out of the heating zone.

2. A machine comprising in combination, pressing members, means for opening and closing the pressing members, tracks supported on the machine and projecting to the front of the machine, said tracks being arranged one above the other, a conveyor

mounted on each track and adapted to roll in and out between the pressing members, one conveyor above the other conveyor, and a connection established between the opening and closing means and the conveyors whereby the conveyors move in and out of the press when the pressing members close.

3. A press and conveyor comprising in combination, cooperating pressing members, a press lever on one end of which is mounted one of the pressing members, motor means cooperating with the other end of the press lever by which the press is opened and closed, conveyor tray supporting means disposed in front of the press, conveyor trays carried by the supporting means and adapted to run in and out of the press, and a connection between the conveyor trays and motor means for synchronously moving the trays in and out during movement of the pressing member.

4. A combination power press and conveyor, press jaws, motor means for opening and closing the press, a pair of work supports, means for guiding the work supports in and out of the jaws, means arranged to guide one work support over the other in opposite direction during the in and out movement thereof, a connection established between the motor means and work supports acting to move the work supports during one movement of the press jaws only, and means causing disconnection of said connection during the other movement of the press jaws.

5. A combination power press and automatic conveyor machine, comprising pressing jaws, power means for opening and closing the jaws, a conveyor adapted to transport the work to and from the jaws, said conveyor embodying a work carrier with an inner portion normally inside the press between the jaws for treatment of the work, and an outer carrier portion standing outside the press adapted to have its work unloaded and replaced while the first named work is under pressure, means joining the inner and outer carrier portions causing one to travel outwardly when the other travels inwardly, and an operating connection cooperating with the power means and with the carrier portions causing the carrier portions to travel in timed relation with the opening and closing jaw motion.

6. A combination press and automatic conveyor machine, comprising pressing jaws, means for opening and closing the jaws, a conveyor adapted to transport the work to and from the jaws, said conveyor embodying a work carrier with an inner portion normally inside the press between the jaws for treatment of the work, and an outer carrier portion standing outside the press adapted to have its work unloaded and replaced while the first named work is under pressure, means

joining the inner and outer carrier portions causing one to travel outwardly when the other travels inwardly, a conveyor connection cooperating with the press jaw opening and closing means whereby the carrier portions travel during the opening and closing motion of the pressing jaws, and means to operate the conveyor connection so it will connect with and disconnect from the carrier portions.

7. A combination power press and automatic conveyor machine comprising pressing jaws, means for opening and closing the jaws, work carrying trays on which the work is placed, means for guiding the trays in and out of the jaws including cross-over means permitting one tray to pass over the other traveling in opposite directions, a connection between the trays, and means connecting the trays with a moving part of the press thereby automatically causing movement of the trays when the press operates.

8. A combination power press and automatic conveyor machine comprising pressing jaws, means for opening and closing the press, trays on which the work is placed, means for guiding the trays in and out of the jaws including cross-over means permitting one tray to pass over the other traveling in opposite directions, a connection between the trays, a linkage arranged to connect the trays with a moving part of the press thereby automatically causing movement of the trays when the press operates, and a disengaging device serving to automatically disconnect the linkage when the press opens.

9. In combination, pressing members, operating means including a moving part connected to one of the members to open and close the press, a pair of work trays and guide means therefor so disposed that one tray is in the press and the other outside thereof, and a driving connection established between the trays and a moving part of said operating means.

10. In combination, pressing members, a lever fixed to one of the members to open and close the press, a pair of work trays so disposed that one is in the press and the other outside thereof, and a driving connection established between the trays and lever, and a releasing mechanism forming part of the driving connection by which the movement of the trays is initiated by one movement of the movable pressing member and caused to stand at rest by the other motion thereof.

11. In combination, pressing members, a lever fixed to one of the members to open and close the press, a pair of work trays so disposed that one is in the press and the other outside thereof, and a driving connection established between the trays and lever, and motor means connected with the lever.

12. In combination, pressing members, operating means for one of the members to open

and close the press, a pair of work trays so disposed that one is in the press and the other outside thereof, a driving connection established between the trays and a moving part of the press, a releasing mechanism forming part of the driving connection by which the movement of the trays is initiated by one movement of the movable pressing member and caused to stand at rest by the other motion thereof, and motor means connected with the operating means for opening and closing the pressing members and automatically driving the trays in and out.

13. A press comprising, pressing members, a lever cooperating with one of the members to open and close the press, a pair of work trays so disposed that one is between the members and the other outside thereof, a driving connection established between the trays and lever, said driving connection comprising a reciprocating carriage slide which runs toward the members as the press closes and moves away as the press opens, and a catch and release means carried on the slide to pick up the trays during travel in one direction and release the trays during travel in the other direction.

14. A press comprising, pressing members, a lever fixed to one of the members to open and close the press, a pair of work trays so disposed that one is in the press and the other outside thereof, a driving connection established between the trays and a moving part of the press, said driving connection comprising a reciprocating carriage slide which runs toward the press as it closes and moves away as the press opens, and a catch and release means carried on the slide to pick up the trays during travel in one direction and release the trays during travel in the other direction, and means arranged to permit relative motion between the trays and driving connection in order that the trays stop moving during imposition of final closing pressure of the pressing members.

15. A press comprising, pressing members, a lever fixed to one of the members to open and close the press, a pair of work trays so disposed that one is in the press and the other outside thereof, a driving connection established between the trays and lever, motor means connected with the lever, and means arranged to permit relative motion between the trays and driving connection in order that the trays stop moving during imposition of final closing pressure of the pressing members.

16. A press comprising, pressing members, a lever fixed to one of the members to open and close the press, a pair of work trays so disposed that one is in the press and the other outside thereof, a driving connection established between the trays and lever, a releasing mechanism forming part of the driving connection by which the movement of the trays is initiated by the opening movement of the

press and caused to stand at rest by the reverse movement thereof, and means arranged to permit relative motion between the trays and driving connection in order that the trays stop moving during imposition of final closing pressure of the pressing members.

5 In testimony whereof I affix my signature.

PHILIP N. BRAUN.
